PAPER DRILLING MACHINE OR THE LIKE

Joseph Adrian, Cleveland, Ohio, assignor to Super Speed Printing Machinery, Inc., Cleveland, Ohio, a corporation of Ohio

Application September 30, 1948, Serial No. 52,019

9 Claims. (Cl. 60—52)

1

This invention relates to power operated drilling machines, and more particularly to power operated paper drilling machines that are used for drilling holes through stacks of paper sheets.

In power operated paper drilling machines, a head that rotatably supports a spindle to which a hollow drill is connected is movable in a vertical direction toward and from a table on which the work is supported; and it is the primary purpose of my invention to simplify the construction and lower the cost of machines of this kind by incorporating, in the head of the machine, not only the mechanism for operating the drill spindle, as heretofore, but also the means for moving the head toward the table in order to force the drill through the work. Thus, all working parts of the machine (excepting a pedal that is used in the present embodiment of the invention for initiating each cycle of operation) are capable of being incorporated in an assembly that terminates at its lower end in a base immediately adjacent the table of the machine, and which assembly is mounted on a stand or cabinet of suitable height.

Another object of the invention is to operate the means for moving the head of the machine toward the table by the same prime mover that drives the drill spindle, and, preferably, to transmit the power from the prime mover to said means through the intervention of the spindle. The obvious advantage in such an arrangement is that, in case the rotation of the drill is obstructed, the operation of the head moving means will be simultaneously arrested thereby to relieve parts of the machine from undue strain or breakage.

Another object is to incorporate hydraulic means in the head of the machine for depressing the head. Another and related object is to make the head of the machine of such form that it will provide a leak-proof reservoir for the liquid used in the hydraulic means, and to locate all parts of said means and the connections through which they communicate inside the reservoir so that in case any leak occurs in said parts or connections the escaping liquid will be confined to the reservoir.

Another object is to provide operative connections between the pedal (located adjacent the bottom of the stand or cabinet) and the operating means (situated in the head of the machine) that will yield readily to the vertical movements of the head and will remain operative at all times notwithstanding the variable spacing between the pedal and the head.

2

A further object of the invention is to incorporate efficient, smoothly operating and durable hydraulic means in the head of a machine of the class aforesaid for depressing the head, and that includes a safety feature for protecting the drill or other parts of the machine against breakage or injury under abnormal operating conditions. An additional object related to the immediately foregoing one is to provide actuating mechanism for the hydraulic means which may be instantly released at any point in the descent of the head thereby to stop such descent and permit the return of the head to normal position.

A still further object is to provide an actuator valve for the hydraulic means that is of very sturdy construction, and that is thoroughly reliable.

The actuator valve above referred to comprises a tubular stem having relief ports, and a valve member in the form of a sleeve that is slidable along the stem to cover and uncover the ports; and it is a further object of the invention to provide means for equalizing the fluid pressure exerted on the interior of the sleeve throughout the circumference and length thereof so as to insure freedom of movement of the sleeve upon the stem. By virtue of this means, and in furtherance of the same end, a film of oil is maintained throughout the area between the sleeve and stem, imparting to the sleeve a sort of floating action.

Another object is to provide dependable trip mechanism for the actuator valve, including an adjustable stop that is especially convenient of manipulation, for causing the valve to operate so as to stop the hydraulic means when the head has descended far enough to insure projection of the drill through the work, but with minimum penetration of the drill block.

The foregoing objects, with others that will appear as this description proceeds, are attained in the embodiment of the invention illustrated in the accompanying drawings, wherein like reference characters designate like parts in the several views; and while I shall describe said embodiment in detail, I wish it to be understood that the invention is not accordingly limited, but is susceptible to such modification and change as fall within the scope of the appended claims.

In the drawings, Fig. 1 is a perspective view of a power operated paper drilling machine incorporating the invention, parts of the stand or cabinet being broken away; Fig. 2 is a similar view of the upper portion of the machine, with the guard that normally encloses the head, and the table, and parts carried by and associated with the table,

omitted; Fig. 3 is a sectional plan view of the head of the machine, the plane of section being indicated by the line 3—3 of Fig. 4; Fig. 4 is a side elevational view in the immediate vicinity of the head of the machine, the head being partly in section, as indicated by the line 4—4 of Fig. 3; Fig. 5 is an enlarged transverse vertical section through the head of the machine, on the line 5—5 of Fig. 3; Fig. 6 is a vertical section through the actuator valve of the hydraulic means, the section being on the line 6—6 of Fig. 5, and Fig. 7 is an enlarged fragmentary view of the valve stem in the region of the escape ports thereof.

1 is a stand or cabinet that is desirably constructed of sheet metal reinforced by structural elements in accordance with common practice. The front of the cabinet is closed partway down from its upper end by a panel 2, and suitably supported within the cabinet, for convenient removal therefrom, is a so-called chip box 3 that is provided with a front plate 4 that closes the front of the cabinet below the panel 2 to within a suitable distance of the floor. The front plate 4 is provided with a "pull" or handle 5. Supported for rocking movement within the front lower portion of the cabinet, on a transverse shaft 6 that has its ends suitably supported in the sides of the cabinet, is a pedal 10, shown as a U-shaped frame. While an operator may depress the pedal by engaging his foot with the front thereof at any point across the machine, the pedal is desirably equipped with a forwardly extending tread 11.

As appears in Fig. 2, an inwardly directed flange 12 surrounds the top of the cabinet, and secured thereto, by fastening means 13, are the front arm 14 and lateral arms 15 of a base designated generally by the reference numeral 20. Rising from the rear of the base at the transverse center thereof, and having its lower end rigidly secured to the base, is a cylindrical column 22, shown as tubular.

A table 24 is suitably fastened to the base 20 and overlies the front portion of the stand or cabinet 1, and projects a distance beyond each side and the front thereof. Removably contained within an opening in the table 24 is the usual circular drill block 27, the opening being so related to the drill that the latter engages the block eccentrically thereof. Surmounting the table and clamped thereto is the customary back gauge 30, and along one end portion thereof is adjustable a side gauge 31.

35 designates, generally, the machine head. This head desirably consists of a casting having a bottom wall 33 and side walls 37 and 38. The rear end of the head is formed by a relatively large vertical sleeve 40 which is slideable upon the before-mentioned column 22. At their forward ends, the side walls 37 and 38 converge and join a smaller vertical sleeve 42. Anti-friction bearings 43 and 44 are shown as seated within counterbores in the upper and lower ends of the sleeve 42 and rotatably support the drill spindle 45 axially of said sleeve. Grooved pulleys 47 and 48 are fastened to the drill spindle above the bearing 43. As is customary in paper drilling machines, the lower end of the spindle has a hollow enlargement 50, provided with one or more side openings, one of which is shown at 51 in Fig. 4. Below said enlargement is the usual drill chuck 53 for connecting a hollow drill to the spindle. Such a drill is shown in Figs. 1 and 2, where it is designated 176. The bore of the chuck opens into the hollow enlargement 50 so that chips from the drill may ascend into said enlargement and be

5 discharged therefrom by centrifugal force through the opening or openings 51 into an annular chamber of a chip housing 55. This housing has a spout-like rearward extension 56 by which the chips are directed into a jointed chip chute 57 (Fig. 1) that leads downwardly through an opening in the table 24 and drops the chips into the chip box 3.

Shown as integral with the head 35, and as located at about the transverse center thereof, immediately in front of the sleeve 40, is a cylinder casing 60, the bore of which opens through the top of the casing. Operating within the bore of the cylinder casing is a piston 62 that may consist of a solid bar of metal that is reduced in diameter at its upper end to provide a stud 63.

65 denotes a beam having a portion that extends diametrically through the column 22 adjacent the upper end of the latter, said portion being provided with cylindrical parts that fit tightly within apertures of the column to rigidly connect the beam to the column. The rectangular front end portion of the beam 65 has a vertical bore that is occupied by the aforesaid stud 63 of the piston. A pin 68 is shown as projected through a transverse hole in the upper end of the stud 63 to lock the beam and piston together. Forwardly of the bore that receives the stud 63, the beam 65 is provided with a vertical, threaded aperture within which an adjusting screw 70 operates, the screw being provided with a knob 71 at its upper end. A threaded, axial recess opens through the lower end of the adjusting screw into which is screwed the threaded upper end of a trip rod 73. A lock nut 74 on said trip rod engages the end of the adjusting screw to bind the parts together when once properly adjusted. The lower end of the rod 73 carries a trip stop 75. To oppose rotation of the adjusting screw 70 and thus hold it against turning as a result of vibration of the machine or other accidental cause, I employ means including a friction block 77, of fiber or the like, which occupies a bore 78 that opens through the front of the beam 65 and into the threaded aperture that is occupied by the screw 70. Said block is forced against the screw by a spring 79 that is compressed between said block and a plug 80 that is threaded into the front end of the bore 78. The trip rod 73 passes freely through a hole in a lug 85 that extends forwardly from the upper end of the cylinder casing 60 and supports a cushion 86 which, in the present instance, consists of a washer of shock absorbing material, such as leather or rubber, that surrounds the trip rod.

50 A relatively stiff helical spring 88 surrounds the column 22 and is compressed between the base 20 and the bottom of the head 35. This so-called "return" spring tends to hold the head in elevated position, with the cushion 86 engaged with the nut 74.

55 A passage 90 extends laterally from the bottom of the bore of the cylinder casing 60 through a thickened part 36a of the bottom wall of the machine head, and communicating therewith is the tubular stem 91 of an actuator valve, designated generally by the reference numeral 92. The lower end of said stem is threadedly connected to the part 36a, and into the lower end of the bore 70 of the valve stem is screwed a plug 94 having an axial aperture for a purpose presently to appear. The valve stem has an enlargement 95 about midway between its ends, and intermediate said enlargement in the lower end of the stem, the latter is provided with radial relief ports 96. 97

is a sleeve-like valve member that is slidably fitted to the stem, and it is normally held in elevated position against the enlargement 95 by a spring 98 that surrounds the lower end of the stem and is compressed between the valve member and the part 36a. To insure freedom of movement of the valve member along the stem, the stem is provided with a series of circumferential grooves 99 that extend a distance above and below and through the zone of the relief ports 96, the character of the grooves best appearing from the enlarged detail of Fig. 7. The presence of these grooves causes a film of oil to be maintained between the adjacent surfaces of the valve member and stem, imparting to said member a sort of floating action as it moves along the stem, and moreover the grooves effect an equalization of pressure of the liquid against the inner surface of the valve member circumferentially and lengthwise of the member. Experience has shown that, in the absence of the grooves, the outward pressure of the liquid on the inner surface of the valve member, when the latter covers the relief ports 96, distorts the valve member enough to result in the latter's binding on the stem. The factors contributing to this condition will be better understood after the operation of the machine has been described.

Mounted for reciprocation on the part of the valve stem 91 above the enlargement 95 is a sleeve 100 having an arm 101 extending laterally from its upper end through a relatively deep notch 102 in the adjacent edge portion of the side wall 37. The sleeve 100 is held elevated, with its upper end engaged with a pipe fitting 103 that is screwed into the top of the valve stem 91, by a helical spring 105 that is compressed between the underside of said arm 101 and a boss 106 that projects from the side wall 37 a distance below the notch 102. This spring surrounds a pull wire 108 that has its upper end locked within a hole in the arm 101 by a set screw 109, while the lower end of said pull wire 108 is connected at 110 (Fig. 1) to the previously mentioned pedal 10. Enclosing all but the end portions of the pull wire is a flexible casing 112, which has its upper end extended through an aperture of the boss 106, wherein it is locked by a set screw 114, and its lower end fastened in a bracket 115 that is attached to a part of the stand or cabinet 1, directly above the connection between the lower end of the pull wire and pedal, by a bolt 116.

A relatively short rock shaft 120 is pivoted intermediate its ends in an apertured lug 121 of the sleeve 100, that is substantially opposite the arm 101. Fastened within a transverse bore of the shaft 120 by a set screw 122, rearwardly of the lug 121, is the upper end of a trip rod 123, the lower end of which is arranged for engagement with the top of the valve member 97, as best shown in Fig. 5. Similarly connected to the front end of the shaft 120, by a set screw 125, is a trip arm 126. Its end remote from the shaft 120 is turned down and disposed in the path of the beforementioned trip stop 75 on the lower end of the rod 73. A spring 128 is coiled about the shaft 120, forwardly of the lug 121, and has one of its ends hooked about said lug, as shown in Figs. 3 and 5, and its opposite end hooked over the trip arm 126, as shown in the aforesaid views, as well as in Fig. 4. This spring is so disposed as to rock the assembly including the trip arm 126, shaft 120, and trip rod 123 in a direction to depress the outer end of said arm and to hold the lower end

of the trip rod toward the stem 91 of the actuator valve 92.

Referring particularly to Figs. 3 and 4, 130 denotes a pump, desirably of the gear type, that is attached to and supported by a bracket 132. This bracket includes a hollow vertical boss 133 into the lower end of the bore of which projects the pump shaft 134. Coupled to the pump shaft is a drive shaft 135 that is journaled in a bushing 136 which occupies the upper portion of the bore of the boss 133, and to the upper end of the drive shaft is fastened a grooved pulley 137. The ends of the pump bracket 132 rest upon lugs 138 and 139 that extend inwardly from the respective side walls 37 and 38, and are fastened to said lugs by screws 140. The pump bracket and parts sustained thereby are omitted from Fig. 5 in order to avoid confusion. The pulley 137 is in the horizontal plane of the previously mentioned pulley 48 that is fastened to the top of the drill spindle 45, and an endless belt 142 extends about said pulleys.

Connected to the inlet side of the pump 130, through an elbow fitting 145, is a pipe 146 that depends to within a suitable distance of the bottom wall 36 of the machine head 35 (Fig. 4). A T fitting 147 has its lateral branch connected to the outlet of the pump and its cross branch arranged in a vertical position. The upper end of said cross branch communicates, through a pipe 15, with the previously mentioned fitting 103 that is connected to the upper end of the valve stem 91. A conventional pressure-relief valve 152 is connected to the lower end of the cross branch of the T fitting 147 and includes a valve closing spring pre-loaded to a given pressure, as will be readily understood by those acquainted with this class of article.

A prime mover in the form of an electric motor 155 is supported by the head 35 through the medium of brackets 156. Said brackets include studs 157 that extend forwardly through bores in lugs 158, shown as integral with and extending laterally from the rear end of the head 35. The studs 157 are adapted to be secured in any position of adjustment within the lugs 158 by set screws 159. The motor 155 is arranged with its shaft 160 vertical, and attached to the shaft directly above the casing of the motor is a fly-wheel 161, and disposed above the fly wheel and fixed with respect to the shaft is a pulley 162. An endless belt 163 is engaged about the pulley 162 and about the previously mentioned pulley 47 that is fastened to the drill spindle 45. Obviously, the tension of the belt 163 may be changed by shifting the motor through the adjustment of its supporting brackets 156.

To prevent leakage or seepage about the piston 62, the wall of the cylinder bore is formed with annular grooves 165 and 166, disposed in suitably spaced relation to each other and to the top of the cylinder casing; and a so-called O-ring 167 (an item well known in the art) occupies the groove 165 and is contracted, through its own resiliency, about the piston 62, and a wiper ring 168 of felt or the like occupies the groove 166.

As a result of the manufacturing method employed, an opening 170, produced by a core support, opens through the bottom of the head 35 in line with the bore of the cylinder casing 60, and this is permanently closed by a sealed-in plug 171; and similarly, a plug 172 permanently closes the outer end of the passage 90. A drain opening for the reservoir constituted of the head 35 is closed by a removable screw plug 173.

A sectional cover may, if desired, be applied to the open top of the machine head 35, such a cover being indicated in broken lines in Figs. 4 and 5, where the cover is designated 174.

The motor 155, with a switch 175, is included in an electric circuit (not shown). In the present instance, said switch is carried by the panel 2 and is located beneath the right hand side of the table where it is in convenient reach of the operator.

A hollow drill 176 (Figs. 1 and 2) is connected, by means of the chuck 53, to the lower end of the spindle 45. 177 is the usual stripper plate, carried by the lower end of a rod 179 that is reciprocable in the bore of a vertical boss 179, shown as an integral part of the head 35. A helical spring 180 surrounds the rod 179 and is compressed between the stripper plate and the bottom of the boss 179, all of this being in accordance with common practice.

A guard 185, shown only in Fig. 1, and desirably fabricated of sheet metal, covers the machine head 35 and encloses the motor 155 and the column 22.

To condition the machine for use, the reservoir provided by the head 35 is filled with oil or other suitable liquid to approximately the depth indicated at X in Figs. 4 and 5.

The machine is set in operation by closing the switch 175 thereby to supply current to the motor 155. With the motor in operation, the drill spindle 45 will be rotated through the driving connections constituted of the pulleys 47 and 162 and the belt 163. With the drill spindle rotating, similar motion will be transmitted to the drive shaft 135 of the pump 130 through the pulleys 48 and 137 and the belt 142. Operation of the pump 130 will set up a circulation of liquid from the reservoir inwardly through the pipe 146, through the pump, and thence through the pipe 150 to the valve stem 91. With the valve member 97 held in elevated position by the spring 98, the liquid will escape through the relief ports 96 to the reservoir, it being understood, of course, that under the present conditions a quiescent body of liquid occupies the lower portion of the bore of the valve stem, the passage 90, and the bore of the cylinder casing 60.

With a stack of paper sheets positioned on the table 24 for drilling, and the stripper plate 177 held firmly in engagement therewith by the spring 180, the operator initiates a drilling cycle by depressing the pedal 10. When the pedal is depressed it draws the pull wire 103 downwardly and, with it, the sleeve 100. This movement of the sleeve is transmitted to the valve member 97 through the trip rod 123. When the valve member is lowered in opposition to the spring 98 it closes the relief ports 96 and causes the liquid from the pump to pass downwardly the length of the valve stem and through the orifice of the plug 94 and thence through the passage 90 to the cylinder bore. Acting against the stationary piston 62, the accumulating liquid under pump pressure forces the head 35 downwardly so as to project the rotating drill 176 through the stack of paper sheets on the table 24. In a normal cycle of operation the head will continue to descend until the drill has penetrated the bottom sheet, at which instant the trip rod 123 will be withdrawn from the upper end of the valve member 97 due to engagement of the trip arm 126 with the stop 75. Thereupon, the spring 93 will lift the valve member 97 above the ports 96, permitting the liquid from the pump, as well as that

from the bore of the cylinder casing 60, to escape to the reservoir. Under these conditions, the spring 98 returns the head 35 to elevated position. However, the flow of liquid from the bore of the cylinder casing is retarded by the restricted orifice of the plug 94, thereby to control the return speed of the head and enable its upward movement to be arrested by engagement of the cushion 26 with the nut 74, without shock.

If, for any reason, the operator desires to stop the drilling operation before the drill has completed its work, he may do so by releasing the pedal 10. This allows the spring 105 to return the valve tripping mechanism to initial position, and permits the valve member 97 to be lifted by the spring 98 so as to uncover the relief ports 96.

In case the drill becomes stuck so as to stop rotation of the drill spindle, the pump will also be stopped inasmuch as it is driven by said spindle, and further depression of the head will be prevented. Under these conditions the operator may immediately open the motor circuit at the switch 175. Again, should the descent of the head be obstructed from any cause, undue liquid pressure is prevented from building up in the system by the opening of the relief valve 152.

Having thus described my invention, what I claim is:

1. In a machine of the class described, characterized by an assembly comprising a base, a work supporting table, and guide means fixed to the base and rising therefrom a substantial distance above the plane of the table; a head sustained by said guide means above the table for movement toward and from the latter, biasing means for elevating the head and tending to retain the head in elevated position, power means incorporated in the head for depressing the head and including a piston and a cylinder of which one is connected to said guide means and the other to the head, the cylinder having an open end through which the piston extends and the piston having a single working face exposed to the interior of the cylinder, a pump also included in said power means for delivering fluid pressure to said cylinder, means operable at will for controlling the delivery of said fluid, a prime mover mounted on the head that is in continual operation while the machine is in use, and constantly effective driving connections between the prime mover and the pump.

2. In a machine of the class described, characterized by a base, a work supporting table, and guide means fixed to the base and rising therefrom a substantial distance above the plane of the table; a head sustained by said guide means above the table for movement toward and from the latter, biasing means for elevating the head and tending to retain the head in elevated position, hydraulic means incorporated in the head and including a piston connected at its upper end to the said guide means in parallel relation thereto, an open end cylinder incorporated in the head and wherein said piston operates, the piston having a single working face exposed to the interior of the cylinder, the head being constructed to provide a reservoir for liquid, a pump carried by the head and having its inlet in communication with the liquid space of said reservoir, communicative connections between the outlet of the pump and said cylinder, a valve in said communicative connections which, when open, permits the escape of the liquid from said communicative connections to the reservoir, means biasing said valve toward open position, manual-

ly operated means for closing said valve, a prime mover mounted on the head, and driving connections through which the prime mover operates said pump.

3. In a machine of the class described, characterized by a base, a work supporting table, and guide means fixed to the base and rising therefrom a substantial distance above the plane of the table, a head sustained by said guide means above the table for movement toward and from the latter, biasing means for elevating the head and tending to retain the head in elevated position, the head being constructed to provide a liquid reservoir, a cylinder incorporated in the head having its axis parallel to the path of movement of the head and opening through the top of the head, a piston within the cylinder having a part extending above the latter, a beam connecting said part of the piston rigidly to said guide means, the piston having a single working face exposed to the interior of the cylinder, a pump carried by the head and having its inlet in communication with the liquid space of the reservoir, communicative connections between the outlet of the pump and the cylinder, a valve in said communicative connections which, when open, permits the escape of liquid from said connections to the reservoir, means biasing the valve to open position, manually operated means for closing the valve, trip mechanism for rendering said manually operated means ineffective when the head reaches the bottom of its stroke, a prime mover mounted on the head, and driving connections through which said prime mover operates the pump.

4. In a machine of the class described, characterized by a base, a work supporting table, and guide means fixed to the base and rising therefrom a substantial distance above the plane of the table; a head sustained by said guide means above the table for movement toward and from the latter, biasing means for elevating the head and tending to retain the head in elevated position, a source of liquid supply in the head, a piston and a cylinder of which one is connected to said guide means, and the other to the head and so arranged as to depress the head when liquid under pressure is supplied to the cylinder, the cylinder having an open end through which the piston extends and the piston having a single working face exposed to the interior of the cylinder, a pump carried by the head and having its inlet in communicative connection with the liquid supply, communicative connections between the outlet of the pump and the cylinder, a valve in said connections which, when open, permits the escape of liquid from said communicative connections to said source of liquid supply, means biasing the valve to open position, manual means for closing the valve, trip mechanism for rendering the manual means ineffective when the head reaches the bottom of its stroke, said mechanism including a stop disposed in a given relation to the guide means, and a trip arm movable with the head for engagement with said stop, a prime mover mounted on the head, and driving connections through which said prime mover operates the pump.

5. In a machine of the class described, characterized by a base, a work supporting table, and guide means fixed to the base and rising therefrom a substantial distance above the plane of the table; a head sustained by said guide means above the table for movement toward and from the latter, biasing means for elevating the head and tending to retain the head in elevated posi-

tion, a piston and a cylinder of which one is connected to said guide means and the other to the head and so arranged as to depress the head when liquid under pressure is supplied to the cylinder, an actuator valve including a tubular stem having a relief port intermediate its ends, and a sleeve-like valve member reciprocable on said stem between a first position in which it uncovers said relief port and a second position wherein it overlies and closes the relief port, the head being formed to provide a liquid reservoir, a pump carried by the head and having its inlet in communication with the liquid space of the reservoir, communicative connections between the outlet of the pump and the cylinder and including the aforesaid valve stem, the relief port of said valve being arranged to discharge into the reservoir, means tending to move the valve member to the aforesaid first position, manually operated means for moving the member to second position, a prime mover mounted on the head, and driving connections through which said prime mover operates the pump.

6. In a machine of the class described, characterized by a base, a work supporting table, and guide means fixed to the base and rising therefrom a substantial distance above the plane of the table; a head sustained by said guide means above the table for movement toward and from the latter, biasing means for elevating the head and tending to retain the head in elevated position, a piston and a cylinder of which one is connected to said guide means and the other to the head and so arranged as to depress the head when liquid under pressure is supplied to the cylinder, an actuator valve including a tubular stem having a relief port intermediate its ends, and a sleeve-like valve member reciprocable on said stem between a first position in which it uncovers said port and a second position wherein it overlies and closes the port, the head being formed to provide a liquid reservoir, a pump carried by the head and having its inlet in communication with the liquid space of the reservoir, communicative connections between the outlet of the pump and the cylinder and including the aforesaid valve stem, said relief port being arranged to discharge into the reservoir, means tending to move the valve member to the aforesaid first position, and manually operated means for moving the member to second position, the valve stem being arranged substantially parallel to the path of movement of the head, and said manually operated means including an element movable longitudinally of the valve stem, a rocking structure having pivotal connection with said element and including a trip rod for engagement with the valve member so as to impart thereto the movement of said element, said rocking structure also incorporating a trip arm that extends laterally from said element, a stop in fixed relation to the guide means for engagement by said trip arm when the head reaches the bottom of its stroke, a prime mover mounted on the head, and driving connections through which said prime mover operates pump.

7. In a machine of the class described, a head, stationary guide means by which the head is supported for reciprocation in a vertical direction, biasing means for elevating the head and tending to retain the head in elevated position, hydraulic means incorporated in the head for depressing it, a liquid supply carried by the head, a pump supported by the head and having its inlet in communication with said liquid supply, communicative connections between the outlet

11

of the pump and said hydraulic means, a valve in said connections which, when open, permits return of the liquid to the liquid supply and, when closed, diverts the liquid to said hydraulic means, means biasing the valve to open position, means for closing the valve, trip mechanism for effecting the opening of the valve, said mechanism being movable with the head and including a trip arm, a stop adjustable with respect to said guide means for limiting the upward movement of the head, and a second stop in fixed relation to the first mentioned stop and adjustable therewith, the second stop being arranged for engagement by said trip arm when the head arrives at the bottom of its stroke, a prime mover, and driving connections between the prime mover and the pump.

8. In a machine of the class described, a head, stationary guide means by which the head is supported for reciprocation in a vertical direction, biasing means for elevating the head and tending to retain the head in elevated position, hydraulic means incorporated in the head for depressing it, a liquid supply carried by the head, a pump supported by the head and having its inlet in communication with said liquid supply, communicative connections between the outlet of the pump and said hydraulic means, a valve in said connections which, when open, permits return of the liquid to the liquid supply and, when closed, diverts the liquid to said hydraulic means, means biasing the valve to open position, means for closing the valve, trip mechanism for effecting the opening of the valve, said mechanism being movable with the head and including a trip arm, a part of the stationary guide means having a threaded aperture, a screw adjustable therein and incorporating a stop for limiting the upward movement of the head, a second stop carried by the screw in fixed relation to the former stop and arranged for engagement by said trip arm when the head arrives at the bot-

12

tom of its stroke, holding means in the aforesaid part frictionally engaging the screw, a prime mover, and driving connections between the prime mover and the pump.

- 5 9. In a machine of the class described, a base, a work supporting table, guide means rising from the base a substantial distance above the plane of the table, a head sustained by said guide means for movement toward and from the table, 10 power means incorporated in the head for moving the latter, an actuator carried by the head for controlling the operation of said power means, an operating member located in a given position relative to the base, and constantly effective 15 operative connections between said operating member and the actuator that yield to the relative movement between the head and base.

JOSEPH ADRIAN.
